ABSTRACT OF THE DISCLOSURE

A protective device for doors, windows and similar closures including a latch cooperable with a strike to lock the closure. The latch is mounted in a lock casing for key-operated displacement between an operative and inoperative position relative to the strike. The lock casing is mounted on the closure for resilient movement away from a home position to an offset position in any one of three modes, respectively in response to forcible displacement of the closure in three directions and a sear is mounted on the lock casing to trigger an alarm when said lock casing is displaced to any one of its offset positions.

The present invention relates to locks of the type in which tampering with the lock discharges a tear gas bomb or other alarm, and is a modification of the device disclosed in U.S. Pat. No. 2,730,970, issued Jan. 17, 1956 to Frank V. Martin.

The patented device was designed for use on wooden doors which are mounted to swing either inwardly or outwardly within an access opening, and such devices have found particular utility in commercial establishments such as stores and warehouses where valuable merchandise is left unattended for extended periods. The patented device is particularly effective not only because of the alarm signal produced by the tampering, but also because of the discharge of tear gas or a similar material which incapacitates the individual tampering with the door and prevents the disabled individual from removing merchandise.

In recent years, the architectural trend has been away from swinging wooden doors and toward metal and glass doors which either swing two ways or slide within the access opening. The metal frame members or stiles of the door are normally much narrower than the conventional wooden framework and the tampering with the door may entail forcible displacement both inward and outward and also in the plane of the door. Accordingly, it has been found invaluable to provide a protective device which is sensitive to forcible displacement of the door in any one of three separate directions and yet is of a sufficiently compact design to be mounted on the relatively narrow stiles of a metallic door.

With the foregoing in mind, the present invention provides an improved protective device which is responsive to forcible displacement of a closure in any one of three directions.

The invention also provides a protective device of a compact design which operates effectively to trigger an alarm, such as an explosive capsule which liberates a disabling gas.

More specifically, the present invention provides a protective device having a latch cooperable with a strike, the latch being mounted in a locked casing which is operable to be displaced to an offset position in response to any tampering which results in forcible displacement of the lock casing relative to the closure in any one of three directions.

Specifically, the illustrated embodiment of the inven-

tion comprises a spring-biased trigger means normally retained cocked against the bias by a sear mounted on the lock casing and operable to be disengaged from the trigger means in the event of tampering which results in forcible displacement of the lock casing.

All of the objects of the invention are more fully set forth hereinafter with reference to the accompanying drawings wherein:

FIG. 1 is a fragmentary view in side elevation of a protective device embodying the present invention;

FIG. 2 is a sectional view taken on the line 2—2 of FIG. 1;

FIG. 3 is a sectional view taken on line 3—3 of FIG. 2;

FIG. 4 is an enlarged sectional view taken on line 4—4 of FIG. 3;

FIGS. 5 and 6 are transverse sectional views taken on the line 5—5 and 6—6 respectively of FIG. 4;

FIG. 7 is an enlarged fragmentary view similar to FIG. 4 illustrating the elements of the protective device in firing position resulting from forcible displacement within the plane of the door opening.

FIG. 8 is a fragmentary view similar to FIG. 5 illustrating the elements of the device in a firing position resulting from forcible displacement of the door away from the plane of the door opening.

FIG. 9 is an enlarged fragmentary sectional view similar to FIG. 3 of a modified protective device incorporating an electrical actuator responsive to tampering; and

FIG. 10 is a view in side elevation at a reduced scale illustrating a device which may be utilized for adjusting the sensitivity of the protective device shown in FIGS. 1 through 8.

In the illustrated embodiment of the invention, the protective device is mounted on the vertical frame member or stile 12 of a metal and glass door 13 mounted for sliding movement in a plane of the door opening to close an access opening 14 having a frame structure 15. The protective device includes a conventional lock casing 16 having a latch 17 adapted to project therefrom to engage in a keeper opening 18 formed in a strike 19 secured to the frame structure 15. Of course, if the thickness of the frame structure permits, the strike may be omitted and the keeper opening for receiving the latch 17 may be formed directly in the metallic frame structure.

In accordance with the invention, an alarm device is provided, having a trigger means mounted adjacent the lock casing 16 and operable upon forcible displacement of the lock casing to trigger or initiate an alarm, as for example, when the door is tampered with or forcible entry is attempted. In the embodiment of the invention illustrated in FIGS. 1 through 8, the alarm device comprises an elongated capsule 22 of a disabling gas such as tear gas, having a cap 23 operable in response to percussive detonation to explode and release the gas from the capsule 22. The trigger means comprises a firing pin 24 mounted in a hollow cylindrical guide 25 for displacement between an active position engaging the cap 23 and an inactive position away from said cap. The pin 24 is biased toward the active position by a compression spring 26 mounted in the guide surrounding a reduced portion of the pin as shown in FIG. 4. The guide member 25 is mounted on the frame structure 12 of the closure 13 by means of a mounting bracket 31 secured to the frame member 12 by suitable fasteners 32 (see FIG. 2). The bracket 31 has upstanding lugs 33 mounting the opposite ends of the guide member 24 in parallel relation to the frame member 12. To accommodate the mechanism to the limited dimensions of the stile, the capsule 22 and cap 23 are mounted parallel to the

guide 25, in the present instance in direct alignment with the firing pin 24, by spring clips 35 projecting from the bracket 31 and are held against the bottom of the guide member 25 by a spring abutment 36.

The firing pin 24 is normally retained in its cocked inactive position by a sear element 42 mounted on the lock casing 16. To this end, the upper end of the firing pin is provided with a circumferential groove 43 providing an annular shoulder adapted to bear on a double-pointed nose portion 44 of the sear element 42, best shown in FIG. 8. Thus upon displacement of the lock casing, the double-pointed nose portion 44 disengages the annular shoulder formed by the groove 43 to release the firing pin 24 for movement to its active position under the bias of the spring 26 to percussively engage the cap 23 and release the gas from the capsule 22.

In accordance with the invention, the lock casing 16 is yieldably mounted on the bracket 31 so that it may be displaced away from its home position, in which the sear nose 44 is operatively engaged in the groove 43, to an offset position in which the nose 44 disengages the groove 43. The yieldable mounting is such that the displacement of the lock casing from its home position may occur in any one of three modes respectively in response to forcible displacement of the door 13 in three directions relative to the frame structure 15, i.e. sliding movement longitudinally within the plane of the opening 14 away from the structure 15, forward lateral movement out of the plane of the opening 14, and rearward lateral movement out of the plane of the opening 14.

In the present instance, the casing 16 is resiliently and yieldably mounted in the door frame member 12. To provide this resilient mounting, the mounting bracket 31 is provided along the free edge of the door with outstanding legs 47 having enlarged apertures 48 therein (see FIGS. 7 and 8) which register with apertured mounting ears 49 projecting from the lock casing 16. The casing 16 is mounted on the bracket by bolts 52 having heads 53 bearing against the ears 49 and nuts 54 threaded on the bolts 52 and bearing against springs 55 which are seated behind the legs 47. The springs 55 therefore urge the ears 49 flush against the front of the legs 47 to normally position the lock casing 16 in the home position illustrated in FIG. 3.

The spring mounting of the lock casing 16 in this manner permits displacement of the lock casing relative to the bracket 31 in the event of attempted forcible entry. Thus, as shown in FIG. 7, if the door is forced away from the framework 15, within the plane of the opening 14, the springs 55 are compressed by the engagement of the latch 17 in the keeper opening 18. When the springs 55 are compressed, the nose 44 of the sear 42 disengages from the groove 43 permitting the firing pin 24 to detonate the cap 23. The displacement of the nose 44 is longitudinal within the plane defined by the perpendicular axes of the pin 24 and the nose 44. On the other hand, if the attempt at forcible entry forces the door 13 out of the plane of the opening, the enlarged apertures 48 permit pivotal movement of the lock casing against the bias of the spring 55, as shown in FIG. 8, as a result of the engagement of the latch 17 in the keeper opening 18. The pivotal movement of the casing 16 on the axis through the fasteners 52 within the plane defined by the pin and the nose displaces the nose laterally out of the plane to disengage the groove and effect detonation of the cap by the pin.

Since the yielding force of the spring against the pivotal movement of FIG. 8 tends to be less than the yielding force against the bodily movement of FIG. 7, it is desirable to provide additional resistance to such pivotal movement so as to avoid inadvertent triggering of the protective device, as for example, when the door is rattled by the wind or by someone trying the door to

determine whether it is locked or open. To this end, deformable guide arms 57 are provided on the sear 42. As shown in FIG. 5, the guide arms 57 diverge outwardly from the sear element 42, the inner arm 57 engaging the mounting bracket 31 and the outer arm 57 engaging a cover element 58 which encloses the protective device. The guide arms 57 are of a strength which permits them to bend, as shown in full lines in FIG. 8, when a predetermined pivoting force is applied to the lock casing 16 through forcible displacement of the closure 13 out of the plane of the access opening 14. When this occurs, the double-pointed nose portion 44 of the sear element 42 disengages the groove 43 and permits the firing pin to detonate the cap 26. To permit escape of the disabling gas from the capsule 22, suitable vents are provided in the cover 58 at 59.

The construction of the protective device is such that it must be inactivated with a key, disengaging the latch 17 from the keeper opening 18. The latch is retracted into the interior of the lock casing 16 in any conventional manner by a lock actuator. The actuator for the latch 17 comprises a driver 61 which passes through a slotted barrel 62 in the lock casing 16 and terminates at one end in a lock cylinder 63 mounted within the frame member 16 and at the other end in a lock cylinder 64 mounted in a housing 65 on the cover members 58. Preferably, the cylinders 63 and 64 have identical tumblers so that the same key may be used to inactivate the protective device from either the inside or the outside of the closure. To prevent unauthorized dismantling of the protective device when it is locked, the cover member 58 is secured to the mounting bracket 31 by means of fasteners 66 whose heads are covered by the strike 19 when the protective device is locked with the latch 17 in the keeper opening 18. To prevent dismantling of the strike from the frame structure, at least one of the fasteners 67 which mount the strike on the frame structure is located behind the latch 17 when the device is locked. As a further precaution, the fasteners 67 may have their heads mutilated after assembly so that they are not readily removed to free the strike from the structure.

The structure of the protective device permits repeated usage of the device by simply replacing the gas capsule. 45 This is accomplished by removing the cover element 58 after unlocking the protective device and displacing the door from the frame structure. With the cover removed, the spent capsule 22 and cap 23 may be simply removed from their spring clips and the firing pin 24 may be driven upwardly in its guide 25 to re-engage the nose 44 of the sear 42 in the groove 43. To facilitate this re-engagement, the free end of the firing pin is conical as indicated at 69 so that upon the upward displacement of the firing pin, the conical portion engages between the points of the nose portion 44 and effects outward displacement of the nose portion so that it may thereafter engage in the groove 43. When the firing pin 24 is thus cocked in its inactive position, a fresh capsule 22 and cap 23 may be inserted in the spring clips. If the triggering of the device entailed bending of a guide arm 57, the bent arm should be returned to its original configuration or replaced with a new one. Thereafter, the cover is replaced and the device is in condition for subsequent firing.

The device of FIGS. 1 to 8 may be modified to operate in conjunction with an electrical alarm system. To this end a single pole, double throw switch is mounted on the mounting bracket 31, for example, as shown in FIG. 9. As shown, the single pole, double throw switch 71 is mounted with its switch operator 72 bearing on the conical tip 69 of the firing pin. The switch terminals 73 are connected into the electrical alarm system as required. In the present instance, three terminals are provided and only two terminals are used. If the alarm system is of the normally open-circuit type in which closure of the circuit could use the alarm, the terminals are connected so that when

the switch is in the illustrated position, the connected terminals are open so that they may be closed when the device is triggered. If the alarm circuit is of the normally closed circuit type wherein an opening in the circuit actuates the alarm, the terminals are connected so that they are closed when in the position shown in FIG. 9 to be opened upon triggering of the protective device. If a combination open-circuit, closed-circuit alarm system is employed, all three terminals are used. It is apparent that when the protective device is used in conjunction with an electrical alarm circuit, the protective device triggers the alarm before the closure is opened and an early warning of an attempted unauthorized entry is obtained. Thus, the gas capsule 22 may be omitted completely if it is desired to avoid contamination of the premises by gas and to rely solely on the electrical alarm system. In other respects, the device of FIG. 9 is identical to the device described above in FIGS. 1 to 8.

The sensitivity of the protective device may be adjusted within wide limits. Such adjustment is accomplished by adjusting the compression of the springs 55 to thereby adjust the yielding force tending to seat the lock casing 16 in its home position wherein the ears 49 bear against the front of the legs 47. The adjustment of the sensitivity is preferably accomplished after the device is installed by displacing the door 13 away from the frame structure to expose the heads 53 of the bolts 52. With the gas capsule 22 and cap 23 removed, the bolts 52 are adjusted until the desired spring force is obtained.

To facilitate adjustment of the spring force, a torque test tool 81 may be used as shown in FIG. 10. The tool consists of a base 82 which is adapted to bear against the frame member 12 of the closure and a hook 83 which is adapted to be engaged with the latch 17. A pointer 84 is mounted on the frame 82 and a handle 85 having a scale 86 thereon is pivoted to the frame by a shaft as indicated at 87. The hook is attached to the handle 85 by a wire rope 88 which is trained over a pulley 89 mounted on the shaft and is engaged with the handle through a bar 90. The engagement is such that when the lock casing 16 is in its home position, the handle 85 is approximately parallel to the frame member.

When adjusting the spring force, the bolts 52 are tightened to firmly seat the lock casing 16 in its home position. The handle is then depressed, deflecting the handle and/or stretching the cable, until the pointer registers with the desired force on the scale and with the handle in this position, the bolts 52 are loosened to the point where the nose 44 is on the point of disengagement from the groove 43. With the bolts 52 adjusted in this manner, the proper spring force urging the lock casing 16 to its home position is obtained. The handle may then be released and the torque tool removed and the gas cartridge and cap replaced in the spring clip.

While a particular embodiment of the present invention has been herein illustrated and described, it is not intended to limit the invention to such disclosure but changes and modifications may be made therein and thereto within the scope of the following claims.

I claim:

1. In a protective device for access openings having a frame structure, and a closure structure normally movable between an open position and a closed position in said frame structure;

a lock casing element having a latch; means mounting said casing element on one of said structures; a strike element; means mounting said strike element the other of said structures in registry with said latch to lock said closure against opening from said closed position when said latch is in operative position; one of said mounting means permitting limited movement of its associated element; yieldable means urging said movable element to a home position; an alarm mechanism having trigger means mounted adjacent said movable element operable between an

active position in which it triggers the alarm mechanism and an inactive position; bias means to urge said trigger means toward said active position; and a sear carried by said movable element in a position when it is in its home position to retain said trigger means in its inactive position against said bias means and operable upon displacement of said movable element from said home position against said yieldable means to effect displacement of said trigger means to said active position;

the improvement wherein said yieldable means affords displacement of said movable element away from its home position to an offset position in any one of three modes respectively in response to forcible displacement of said closure away from its closed position in three directions relative to said access opening, said trigger means comprising an elongated element having a transverse groove therein, and said sear includes a nose portion engaged in said groove when said casing is in its home position and disengaged from said groove upon displacement of said movable element transversely outward to said offset position in any one of three directions transverse to said elongated element.

2. A protective device according to claim 1 wherein said trigger means is an elongated pin substantially perpendicular to said nose portion and said yieldable means mounts said movable element and said nose portion for movements longitudinally away from said groove within a plane defined by said nose portion and said pin, laterally away from said groove in one direction out of said plane, and laterally away from said groove in the opposite direction out of said plane, to thereby release said pin for longitudinal displacement to its active position by said bias means.

3. A device according to claim 2 wherein said yieldable means includes fasteners interconnecting said movable element to its associated mounting means for both movement longitudinally of said nose portion and pivotal movement on said fasteners in either clockwise or counterclockwise direction about an axis in said plane transverse to and spaced from said nose means.

4. A device according to claim 3 wherein said fasteners comprise nuts and bolts and spring means biasing said movable element to its home position; said movable element and its mounting means having apertures receiving said bolts with sufficient clearance to afford either said longitudinal or said pivotal movement upon yielding of said spring means, said nuts being adjustable on said bolts to vary the biasing force of said spring means.

5. A tool for adjusting a device according to claim 4 including a base adapted to engage said mounting means, a pivot on said base, a handle mounted on said pivot, pulley carried by said handle, and a cable secured to said handle, trained over said pulley and engageable with said movable element whereby a predetermined displacement of said handle tensions said cable to exert a predetermined force against said movable element tending to displace it longitudinally of said nose against the bias of said spring means so that the biasing force of said spring means may be adjusted to equal said predetermined force.

6. A device according to claim 2 wherein said yieldable means includes deformable means on said sear engageable with said closure to yieldably resist said lateral movement of said nose portion.

7. A device according to claim 2 wherein said groove circumscribes said pin to provide an annular shoulder and said nose portion comprises a double-pointed element engageable with said annular shoulder, said pin terminating adjacent said groove in a conical tip cooperable with said double-pointed element to displace said nose portion affording re-engagement of said element in said groove.

8. A device according to claim 1 wherein said alarm mechanism includes a gas capsule and a cap which may

be percussively detonated to release the gas from said capsule, said trigger means comprising a firing pin for said cap.

9. A device according to claim 1 wherein said alarm mechanism includes an electrical switch responsive to displacement of said trigger means to its active position to energize an alarm.

10. A device according to claim 9 wherein said switch is a single-pole, double-throw switch operable to control both a normally-closed and a normally-open alarm circuit.

11. A tool for exerting a predetermined force against a movable element of a protective device for a closure, comprising a base adapted to engage said closure, a pivot on said base, a handle mounted on said pivot, pulley carried by said handle, and a cable secured to said handle, trained over said pulley and engageable with said element whereby a predetermined displacement of said handle deflects said handle and/or tensions said cable to exert a predetermined force against said movable element tending to displace said element away from its mounting.

12. In a protective device for access openings having a frame structure, and a closure structure normally movable between an open position and a closed position in said frame structure;

a lock casing element having a latch; means mounting said casing element on one of said structures; a strike element; means mounting said strike element on the other of said structures in registry with said latch to lock said closure against opening from said closed position when said latch is in operative position; one of said mounting means permitting limited movement of its associated element; yieldable means urging said movable element to a home position; an alarm mechanism having trigger means mounted adjacent said movable element operable between an active position in which it triggers the alarm mechanism and an inactive position; bias means to urge said trigger means toward said active position; and

5

10

15

20

25

30

35

40

a sear carried by said movable element in a position when it is in its home position to retain said trigger means in its inactive position against said bias means and operable upon displacement of said movable element from said home position against said yieldable means to effect displacement of said trigger means to said active position;

the improvement wherein said alarm mechanism includes an elongated gas capsule having an end cap engageable by said trigger means to be percussively detonated upon endwise impact for releasing the gas from the capsule; and said trigger means comprises an elongated pin parallel to said capsule and having a reduced portion, a groove at one end when in its inactive position engageable with said sear, and firing means at the opposite end to provide endwise impact upon said end cap of the capsule and trigger said alarm mechanism when said pin is in its active position, a hollow cylindrical guide mounting said pin for longitudinal displacement therein, said bias means comprising a compression spring surrounding said reduced portion of the pin within said guide to displace said pin to its active position upon disengagement of said sear from said groove.

13. A device according to claim 12 wherein said groove is a circumferential groove surrounding said pin providing an annular shoulder adapted to bear upon said sear, said pin terminating immediately beyond said groove in a conical tip so as to insure disengagement of said sear from said pin upon longitudinal displacement of the pin in a direction toward its active position.
